DESIGN FOR A HANDBAG FRAME

Charles Karron, Brooklyn, N. Y.

Application February 3, 1940, Serial No. 89,968

Term of patent 3½ years

To all whom it may concern:

Be it known that I, Charles Karron, a citizen of the United States and resident of Brooklyn, New York, in the county of Kings and State of New York, have invented a new, original, and ornamental Design for a Handbag Frame, of which the following is a specification, reference being had to the accompanying drawing, forming part thereof.

Fig. 1 is a front elevational view of a handbag frame, showing my new design.

Fig. 2 is a top plan view of the same.

Fig. 3 is an enlarged perspective view of one of the fastener elements shown in Figs. 1 and 2.

The dominant features of my design reside in the portions shown in full lines.

I claim:

The ornamental design for a handbag frame, as shown and described.

CHARLES KARRON.
